UNITED STATES PATENT OFFICE.

HORACE DUMARS, OF NEW YORK, N. Y.

APPARATUS FOR ILLUMINATED DISPLAYS.

1,230,878.

Specification of Letters Patent. Patented June 26, 1917.

Application filed August 18, 1916. Serial No. 115,632.

To all whom it may concern:

Be it known that I, HORACE DUMARS, a citizen of the United States, and a resident of New York, in the county and State of New York, have invented certain new and useful Improvements in Apparatus for Illuminated Displays, of which the following is a specification.

The invention relates to a method of exhibiting, advertising and like illuminated displays, and to devices which may be used in connection with same. The objects and advantages of the invention will be set forth in part hereinafter and in part will be obvious herefrom, or may be learned through practice with the invention, the same being secured through the means and instrumentalities pointed out in the appended claims.

The accompanying drawings referred to herein, and constituting a part hereof, illustrate by way of example one embodiment of the invention, the same serving in connection with the description to explain the principles of the invention.

25 Of the drawings:

Figure 1 is a central longitudinal section of a device embodying the invention;

Fig. 2 is a view representing a picture at the exhibition locus and also at the illumination locus;

Fig. 3 is a horizontal fragmentary section on an enlarged scale, centrally through Fig. 2.

Fig. 4 is a picture at the exhibition locus of a somewhat different form, and also at the illumination locus;

Fig. 5 is a fragmentary transverse section, on the line C—D of Fig. 4;

Fig. 6 is a vertical fragmentary section, on the line E—F of Fig. 4.

Herein, the place at which the design is illuminated is conveniently called the illumination locus and the place at which the picture is presented to the view of an observer is called the exhibition locus.

Referring to the accompanying drawings, illustrating, by way of example, an embodiment of the invention, there is presented at the illumination locus a composite and relatively movable design, having two or more design elements which receive and reflect the light, and thereby provide at the exhibition locus a united visual effect due to the relative positioning and relative move-

ment of the design elements, presenting at 55 the exhibition locus a single picture adapted to catch both the attention and fancy of a casual and primarily uninterested observer, and also strikingly and suggestively illustrative of the uses and advantages of the 60 article advertised.

By way of example, in Figs. 2 and 3 of the drawings is exemplified an advertisement for a paste dentifrice sold in tube form. There is presented at the exhibition locus, not only a facsimile pictorial representation of the tube as purveyed, but through the arrangement, coaction and relative movement of the design elements, there is also presented a continuous and changing 70 representation of the manner of dispensing the dentifrice from the tube for use. There is thus an objective and wordless reminder of the neatness, cleanliness, economy, facility, and hygiene of this particular manner of packing, handling and using a dentifrice. By the arrangement, coaction and relative movement of the design elements, which thus coöperate to show a unitary picture at the exhibition locus, the exceedingly novel 75 and attractive effect is secured of a changing and ample descriptive or laudatory legend relating to the advertised commodity, which has also the additional attractive features of the peculiar and interesting relation of 80 the legend to the goods (the legend appearing on the exuding ribbon of tooth paste), and the consequent illustration of the manner of using same. There is also the further valuable advantage that the descriptive or 85 laudatory legend is only gradually disclosed to the observer, thus stimulating his curiosity, and also keeping continuously before his attention the advantages of the manner of shipping, dispensing and using the commodity.

In Figs. 4 to 6 of the drawings the invention in certain of its features is exemplified as applied to an advertisement for a motor car, the relatively permanent element of the 100 design or picture creating instrumentality in this case being the motor car, and the traveling or relatively transitory element being the landscape or a portion thereof. It will be understood that there is likewise embodied together in this exemplification definite descriptive or laudatory matter, which is changing and progressing coexistent and 105

simultaneous with the objective suggestion and illustration of the pleasures and benefits of motoring, such as the continually changing scene and the exhilaration of motion, which effects are obtained through the relative positioning, coaction and relative movement of the design elements at the illumination locus.

Referring in detail to Fig. 1 of the drawings, suitable light-producing means are provided, such as lamps 1, arranged within a casing frame and provided, respectively, with reflectors 4. The lamp projects its light upon the design elements at the illumination locus, the light being reflected from the design and projected to produce a unitary picture and effect, as pointed out and described, at the exhibition locus. A suitable lens or lenses 7 are provided, supported 20 in a lens tube 8.

The relatively permanent element of the design in the exemplification of Figs. 2 and 3 consists of a representation of a tube 10 of a dentifrice. This representation, so far 25 as concerns many features of the invention, might be an actual tube, a lithograph or other picture thereof, the backing 12 therefore being cut or conformed to the exterior outline of the tube, or being of a neutral 30 or light absorbing or non-reflecting color, such as black.

The progressive and changing descriptive or laudatory matter in Figs. 2 and 3, so far as it is visible in the picture at the 35 exhibition locus, comprises reading matter carried upon a moving ribbon of the dentifrice paste emerging from the service slot 11 in the end of the tube 10, just as the 40 paste would be dispensed on to a tooth brush for actual use. An endless traveling band 15 is provided running over a series of pulleys 16, arranged to dispose the band to give maximum or adequate length thereto within the available space. Thus 45 in the exhibited picture the ribbon of tooth paste is continually emerging from the tube just as a user would eject it onto his tooth brush, and on the surface of the ribbon of paste is the progressive legend descriptive 50 or laudatory of the paste.

The band is driven in a suitable manner, as from a motor 17, driving one or more of the pulleys 16 by a suitable connection, such as a belt and pulley drive 18. 55 The band 15 is led up to and behind the support 12 for the representation of the tube and positioned just back of the representation of the service slot 11 in the tube, the running band 15 emerging into the field 60 of visibility and of illumination first at this point, thereby giving the various effects desired and already described or referred to, together with others which will be obvious, 65 or which may be learned through experience 70 with or observation of the invention in prac-

tical operation. The support 12 may be beveled as shown at 19 in Fig. 3, and a pulley or pulleys 20 may be employed to direct the band 15 in an accurate and realistic manner as it emerges into the field of illumination at the illumination locus.

Referring to the illustrated exemplification of Figs. 4 to 6 inclusive, the invention is shown representing at the exhibition locus an automobile running along a country road, the automobile remaining relatively permanently in the illumination locus, while the landscape back of the car is made to travel, the various descriptive or laudatory statements being preferably presented in such instance as sign boards arranged along the roadway. The wheels of the motor car are also made to rotate at a speed corresponding to the travel of the passing landscape.

Referring more particularly to the specific mechanism shown, a backing 25 is shaped or apertured, as by vertically arranged slots 26 and 27 to guide and support a traveling band 28, upon which band the landscape is pictured. The web 28 is further suitably guided and supported, as by pulleys 29 and 30, which pulleys are driven in a suitable manner by a motor 31. The representation of the motor car 32 is cut out and supported in front of the web or band 28 by brackets 33, the roadway being represented upon a relatively permanent member 34. The wheels 35 and 36 of the motor car are shown mounted on shafts 37, projecting backwardly through the support 25. The shafts 37 are driven in a suitable manner, as by pulley or pulleys 38, and a belt 39, which belt is driven from a motor 31.

It will be understood that the general characterization of the invention applies 105 to the exemplification just described and it need not be repeated at this point.

What I claim as my invention is:

1. In an advertising display or like device, the combination of a member representing a commodity package, and a traveling member representing the commodity being dispensed from the package, said traveling member bearing a legend relating to the commodity.

2. In apparatus for displaying an article of merchandise for advertising purposes, the combination of a stationary member representative of the article, a moving member associated with the stationary member 120 adapted to depict movement characteristic of the use of the said article and bearing and displaying a legend relating to the article.

3. In apparatus for displaying an article 125 of merchandise for advertising purposes, the combination of a stationary member representative of the article, a moving member associated with the stationary member adapted to depict movement characteristic 130

of the use of the said article and bearing
and displaying a legend relating to the ar-
ticle, and means for illuminating said sta-
tionary and moving members and project-
ing an image thereof upon a suitable dis-
play surface.

5 In testimony whereof, I have signed my

name to this specification, in the presence
of two subscribing witnesses.

HORACE DUMARS.
